John Schuman.
E. Sculley,

Inventor:

Richard Watson.
by his Atty
W. J. Sprague

UNITED STATES PATENT OFFICE.

RICHARD WATSON, OF DETROIT, MICHIGAN, ASSIGNOR OF ONE-HALF TO
JOHN GRANT, OF SAME PLACE.

VELOCIPED.

SPECIFICATION forming part of Letters Patent No. 363,189, dated May 17, 1887.

Application filed January 13, 1887. Serial No. 221,178. (No model.)

To all whom it may concern:

Be it known that I, RICHARD WATSON, of Detroit, in the county of Wayne and State of Michigan, have invented new and useful Improvements in Tricycles; and I do hereby declare that the following is a full, clear, and exact description thereof, reference being had to the accompanying drawings, which form a part of this specification.

10 This invention relates to certain new and useful improvements in tricycles.

The invention consists in the peculiar construction and arrangement of sprocket-wheels and the drive-shaft for rotating the rear axle directly by the pedal action, in the construction and application of means for regulating the tension of the drive-chain, and in the peculiar construction, arrangement, and combination of the various parts, all as more fully 20 hereinafter set forth.

Figure 1 is a perspective view of my improved tricycle, and Fig. 2 is a top plan of the same. Fig. 3 is a detail, referred to hereinafter.

25 In the accompanying drawings, which form a part of this specification, A represents the backbone, which supports the seat B. The forward end of this backbone is pivotally secured to the steering rod or post C, while its rear end is bifurcated, as shown, and is provided with proper bearings for the rotating shaft D, which carries the rear wheels, E. The lower end of the steering-post C is bifurcated, as shown, and carries the steering- 30 wheel F.

35 G are parallel reach-bars, the forward ends of which are connected to a Y-piece, H, the latter being pivotally secured in any proper manner to the steering-post. The rear ends 40 of these reach bars or rods G are bent outwardly and secured to the bifurcated arms of the backbone.

I is a yoke, the upper end of which is secured to the backbone, while the lower ends 45 of such yoke engage with T-pieces J, which form the upper half of a clamp-box, K, (shown in Fig. 3,) being provided with a journal-bearing, L, for the reception of the shaft M, to which is secured the treadle-levers N.

O is a sprocket-wheel secured upon the shaft 50 M between the arms of the yoke I.

P is a similar sprocket-wheel secured upon the rear axle or shaft, D, and R is an endless drive-chain, engaging with and driven by these sprocket-wheels. In securing the lower 55 ends of the yoke I to the rear bars in the manner described, it will readily be seen that the lower ends of such yoke can be readily moved forward or backward by releasing the clamp-boxes and again securing them to the reach-bars, thereby affording efficient means for taking up the slack or regulating the tension of the drive-chain.

The sprocket-wheel O, being much larger in diameter than the wheel P, enables the rider to 60 propel the machine at a very high rate of speed. He has also all the benefits that may arise from the use of a bicycle without the danger of upsetting or taking "headers."

What I claim as my invention is—

1. A tricycle-frame consisting of the backbone A, steering-post C, reach-bars G, and yoke I, all connected together, and the Y-shaped piece H, connecting said reach-bars and steering-post, substantially as described. 70

2. The combination of the backbone A, steering-post C, and reach-bars G with the yoke I and clamp-boxes K on said bars, and engaging the lower end of said yoke, said boxes being formed of T-shaped pieces J, substantially as and for the purposes described. 75

3. In a tricycle, the combination of the backbone A, steering-post C, pivotally secured to the forward end of said backbone, shaft D, wheels E F, reach-bars G, pivotally secured at their front ends to the post C, yoke I, adjustable upon the reach-bars G, clamp-boxes K, shaft M, treadle-levers N, sprocket-wheels O P, and drive-chain R, when constructed, arranged, and operating substantially 80 in the manner and for the purposes specified. 85

RICHARD WATSON.
